UNITED STATES PATENT OFFICE.

RAYMOND F. HAUSEN, OF PITTSBURGH, PENNSYLVANIA, ASSIGNOR TO PITTSBURGH CARBON BRUSH COMPANY, A COPARTNERSHIP COMPOSED OF GEORGE F. STIMPLE AND RAYMOND F. HAUSEN, OF PITTSBURGH, PENNSYLVANIA.

CARBON BRUSH.

1,104,115.

Specification of Letters Patent. Patented July 21, 1914.

Application filed December 19, 1913. Serial No. 807,618.

To all whom it may concern:

Be it known that I, RAYMOND F. HAUSEN, a citizen of the United States, and resident of Pittsburgh, in the county of Allegheny and State of Pennsylvania, have invented a new and useful Improvement in Carbon Brushes; and I do hereby declare the following to be a full, clear, and exact description thereof.

10 My invention relates to carbon-brushes for dynamos, motors and other electrical machines, and more especially to the means for attaching conductors to said brushes.

The object of my invention is to provide 15 for the securing of the conductor to the carbon-brush in such a manner that the conductor is secured rigidly in position, so that it cannot work loose and virtually becomes an integral part of the brush itself.

20 To these ends, my invention consists, generally stated, in driving a screw into the conductor, which has been inserted in an opening formed for it in the brush, the threads of the screw working their way into 25 the strands of the conductors and forming its own screw-threads therein, the size of the opening in the brush being such that when the screw has been driven in, it forces the strands of the conductor against the carbon 30 and the threads of the screw act to hold and bind the conductor so as to prevent its working loose, and in such manner that it practically becomes an integral part of the brush itself.

35 In the accompanying drawing, Figure 1 is a view of a brush partly cut away to show the opening for the insertion of the conductor, and the conductor is shown as inserted in said opening; Fig. 2 is a like view, 40 showing the conductor opened out by a sharp pointed tool to receive the screw; Fig. 3 is a like view showing a screw driven into position; Fig. 4 is a perspective view of the carbon-brush with the conductor screwed 45 therein, and Fig. 5 is a section on the line 5—5, Fig. 4.

Referring to the drawings, the numeral 2 designates the carbon-brush which may be of any suitable construction, provided with 50 the aperture or passage 3 to receive the conductor 4, which may be of the ordinary woven type or of the strand type as may be desired. This conductor is inserted in the passage 3 and when inserted therein a sharp

tool or instrument is forced into the inner 55 end of the conductor to open it up in the manner indicated in Fig. 2. The screw 5 is inserted in the open end of the conductor 4, inserted within the passage 3 as above set forth, and the screw is screwed into position 60 by a screw-driver, the threads of the screw biting into and forming a corresponding thread in the metal of the conductor, so that when the screw is screwed into place, it has the appearance shown in Fig. 3. 65

The screw may be of such a length as to extend entirely through the brush, or only part way through the same, as illustrated, and when once in place, the end of the screw may be cut off to destroy the seat for the 70 screw-driver, so that when once the conductor has been secured in place, it cannot be withdrawn or tampered with. These screws may be formed of a soft metal, such as brass, and the head may be twisted off, leaving the 75 screw flush with the brush.

As stated above, while I have illustrated my invention in connection with a woven conductor which can be opened up by a sharp tool to receive the screw, I do not 80 wish to limit my invention to such form of conductor, as the ordinary twisted conductor formed of strands may be employed, as the screw will force its way into and form the threads in such a conductor, equally as 85 well as in the form of conductor illustrated.

The opening in the brush is made of such a size that when the screw is driven into place, the metal of the screw and that of the conductor will fill completely up the opening in the brush, and the screw and conductor become practically an integral part of the brush as indicated in Fig. 5.

By screwing the screw into position, it is gradually worked into place and it does not 95 have a wedging action which tends to break the carbon, but it moves in so gradually and bites its way into the metal of the conductor, which yields and so relieves the strain on the carbon of the brush, while at the same time, 100 when once in place, the withdrawal of the conductor is practically impossible without destroying the brush, and it cannot work loose. Where expansion takes place the threads of the screw will offer relief by biting further into the conductor, which will 105 prevent the liability of the cracking or breaking of the carbon brush.

By this construction, the brush cannot be tampered with nor can the conductor be removed to insert another one, which prevents inexperienced persons from inserting old conductors in other carbon-brushes, which may not be of proper size to carry the current which the brush may be called upon to carry.

What I claim is:

10 In a collecting brush for dynamos, motors, etc., the combination of the carbon-

brush, having an opening therein, a conductor in said opening, and a screw in said opening engaging said conductor and forming threads in the metal of said conductor. 15

In testimony whereof, I the said RAYMOND F. HAUSEN, have hereunto set my hand.

RAYMOND F. HAUSEN.
